UNITED STATES PATENT OFFICE.

JOHN C. COOK, OF CHICAGO, ILLINOIS.

GRIPPER-FINGER MECHANISM FOR PRESSES.

1,111,364.

Specification of Letters Patent. Patented Sept. 22, 1914.

Application filed April 29, 1914. Serial No. 835,064.

To all whom it may concern:

Be it known that I, JOHN C. COOK, a citizen of the United States, and a resident of Chicago, in the county of Cook and State 5 of Illinois, have invented certain new and useful Improvements in Gripper-Finger Mechanism for Presses, of which the following is a full, clear, and exact specification.

10 My invention is concerned with certain new and useful improvements in gripper-finger mechanism for holding single sheets of paper upon a plate for printing or some such purpose, and is designed to produce a 15 simple structure in which a plurality of fingers can be simultaneously lifted by a single movement, and which fingers shall nevertheless be capable of independent movement and adjustment, so that each 20 finger will naturally engage the paper beneath it in spite of any variations that may exist in the thickness thereof at the different points where the fingers engage the paper.

To illustrate my invention, I annex here- 25 to a sheet of drawings, in which the same reference characters are used to designate identical parts in all the figures, of which—

Figure 1 is a top plan view of a portion 30 of a lithograph press having my invention applied thereto; and Fig. 2 is a vertical section on an enlarged scale.

I have shown my invention as applied to a lithograph press in which the plate *a* upon which the paper to be printed is placed 35 is a part of the main framework. Mounted in bearings *b* secured on the top of the frame is the rod *c*, upon which a plurality of gripper-fingers *d* are pivoted, as best seen in Fig. 2. These fingers have a stepped 40 aperture *e* in the rear portion thereof, and a rod *f*, having a head thereon coöperating with the shoulder in the aperture *e*, extends down through each gripper, through an aperture *g* in the bed-plate, and rests on the 45 eccentric shaft *h*, which is journaled in suitable bearings in the frame, and is provided with a handle *i* by which it may be rocked from one position to another. The lower ends of these rods *f* are guided in a bar *j* 50 extending across the frame and having as many apertures therein through which the rods pass as there are rods. The upper end of the rod beneath the dog is surrounded by a loose sleeve *k*, which terminates in or ex- 55 tends to a washer *l* at the lower end thereof.

A rather strong helically-coiled expanding

spring *m* is interposed between the washer *l* and an abutment *n* secured on the rod, which abutment preferably takes the form of a cupped nut screwed on the threaded lower 60 end of the rod and secured in place by the lock-nut *o*. Between the washer *l* and the under side of the top of the frame, I secure a much weaker helically-coiled expanding 65 spring *p*.

The action of the mechanism just described is as follows: The springs *m* are of such a length that when the handle *i* is turned to the position shown, in which it is stopped by the lug *q* secured on the handle 70 coöperating with the stop-pin *r* on the frame, the high part of the eccentric engages the bottoms of the rods *f* and holds them up, as shown, so that the helically-coiled expanding spring *m* is compressed 75 and acts on the washer *l* to lift the same, and this in turn lifts the sleeve *k*, which lifts the rear end of the dog *d*, so that the front end is forced down on the paper beneath it to hold it securely in position. The amount 80 that this spring *m* is compressed is preferably less than the eccentricity of the bar *h*, so that when said bar is swung to the opposite position, in which the lug *q* contacts with the other stop-pin *s*, the spring *p* 85 coöperating with the washer *l*, and acting through the spring *m* and the nut *n* against the rod *f*, forces said rod down, the rod being free to descend on account of the lower part of the eccentric being uppermost. The action of this spring *p* thus forces the rod *f* 90 down, and its head engages with the shoulder in the aperture *e*, and draws that end of the dog down, thus raising the front end so as to release the sheet of paper held 95 thereby.

It will be noted that, owing to the fact that each finger *d* is loose on the rod *c* and has its own springs, the dog can act certainly against the paper that may be beneath it, whatever its thickness may be relative to the paper beneath the other dogs. 100

While I have shown and described my invention as embodied in the form which I at present consider best adapted to carry out its purposes, it will be understood that it is capable of modifications, and that I do not desire to be limited in the interpretation of the following claims except as may be necessitated by the state of the prior art. 105

What I claim as new, and desire to secure by Letters Patent of the United States, is:

1. In a device of the class described, the combination with a plate, of a bearing rod supported above the plate, a plurality of fingers independently pivoted on the rod 5 coöperating with the plate, a spring for each finger tending to hold it in engagement with the plate, an eccentric rock-shaft, a headed rod for each finger resting on the rock shaft and passing through an aperture 10 in the finger, and means for forcing the rod down to lift the fingers when the eccentric shaft is rotated to permit downward movement of the rod.

2. In a device of the class described, the combination with a support, of a finger pivoted thereon, a headed rod passing loosely through an aperture in the finger, an eccentric shaft on which the rod rests, means 15 for rocking the shaft, and spring mechanism for holding the finger in engagement 20 with the support.

3. In a device of the class described, the combination with a support, of a finger pivoted thereon, a headed rod passing loosely 25 through an aperture in the finger, an eccentric shaft on which the rod rests, means for rocking the shaft, a sleeve surrounding the rod and engaging the under side of the finger, and a helically-coiled expanding 30 spring surrounding the rod and interposed between the lower end of the sleeve and an abutment on the rod.

4. In a device of the class described, the combination with a support, of a finger 35 pivoted thereon, a headed rod passing loosely through an aperture in the finger, an eccentric shaft on which the rod rests, means for rocking the shaft, a sleeve surrounding the rod and engaging the under 40 side of the finger, and a helically-coiled expanding spring surrounding the rod and interposed between the lower end of the

sleeve and an abutment on the rod, said abutment consisting of a nut screwed thereon so as to adjust the tension of the spring. 45

5. In a device of the class described, the combination with a support, of a finger pivoted thereon, a headed rod passing loosely through an aperture in the finger, an eccentric shaft on which the rod rests, means 50 for rocking the shaft, a sleeve surrounding the rod and engaging the under side of the finger, a helically-coiled expanding spring surrounding the rod and interposed between the lower end of the sleeve and an 55 abutment on the rod, and a second spring interposed between the bottom of the sleeve and the support.

6. In a device of the class described, the combination with a plate, of a bearing rod 60 supported above the plate, a plurality of fingers independently pivoted on the rod coöperating with the plate and having apertures through the rear ends thereof, an eccentric rock-shaft located beneath the fingers, a headed rod for each finger passing through the aperture therein and resting on the rock-shaft, an abutment on each rod, a helically-coiled expanding spring surrounding each rod and resting on the abutment, a washer on top of each of said 70 springs, a sleeve resting on each of said washers and engaging the under side of the rear end of the finger associated therewith, and a helically-coiled expanding spring surrounding each sleeve and interposed between its washer and a stationary abutment. 75

In witness whereof, I have hereunto set my hand and affixed my seal, this 21st day of April, A. D. 1914.

JOHN C. COOK. [L. s.]
